UNITED STATES PATENT OFFICE.

ERIC BLUCKER, OF CHICAGO, ILLINOIS.

STEAM TURBINE.

Application filed May 12, 1923. Serial No. 638,473.

To all whom it may concern:

Be it known that I, ERIC BLUCKER, a citizen of the United States, residing in the city of Chicago, in the county of Cook, in 5 the State of Illinois, have invented certain new and useful Improvements in Steam Turbines, of which the following is a specification, reference being had to the accompanying drawings, forming a part thereof.

10 The purpose of this invention is to provide an improved construction of a steam turbine motor adapted for more economical development of power than has been obtained in motors of this type heretofore. It 15 consists in the elements and features of construction shown and described as indicated in the claims.

In the drawings:—

Figure 1 is a side elevation of a motor 20 embodying this invention.

Figure 2 is an edge elevation of the same.

Figure 3 is a horizontal axial section at the line, 3—3, on Figure 1.

25 Figure 4 is a detail section at the line, 4—4, on Figure 3.

Figure 5 is an inner face view of one member of the rotor casing.

Figure 6 is a section at the line, 6—6, on 30 Figure 5.

Figure 7 is an inner face view of the complementary member of the casing.

Figure 8 is a section at the line, 8—8, on 35 Figure 7.

Figure 9 is an enlarged detail elevation 40 showing a limited segment of the pocketed casing wall with which the rotor co-operates, said casing wall being formed in two laminae of which the inner one is partly broken away to disclose the structure of the other at the parting plane.

Figure 10 is a detail section at the arc, 45 10—10 on Figure 9.

Figure 11 is a detail section at the line, 11—11, on Figure 9.

Figure 12 is a section of a small segment 50 of the rotor in an arc through a selected series of its pockets as at the arc, 12—12, on Figure 13.

Figure 13 is a face view of a segment of the rotor.

The turbine shown in the drawings comprises a rotor, 1, mounted on a power-transmitting shaft, A, journaled in a two-part casing comprising members, 2 and 3, of 55 which the member, 2, comprises a trans-axial web 2^m and a cylindrical flange 2ⁿ

therefrom, rendering it cup-shaped and the member, 3, is a flat disk forming a cover or closure for the member, 2, the rotor being fitted for rotation between the two 60 members, 2 and 3, in contiguity at its opposite faces with the inner faces of said case members respectively. The rotor is formed upon its opposite faces with a plurality of concentric series of pockets, 1^a, 65 said pockets being concavely curvilinear, both in circumferential section and in radial section, as may be understood from Figures 12 and 3, respectively; and for reducing the thickness of the rotor disk to the 70 least dimension, the series of pockets upon one face are desirably opposite the bridges or intervals between the corresponding series of pockets upon the opposite face, as seen in Figure 3, and the pockets in each 75 series on one face are opposite the intervals between the pockets of the corresponding series upon the opposite face, as seen in Figure 12. The casing members are each formed upon the inner face with concentric series of pockets, 4, corresponding to and facing respectively the series of rotor pockets, 1^a, on the contiguous faces respectively, of the rotor disk. The pockets, 4, are concavely curved in circumferential section, as seen in Figure 10, being angularly trapezoidal in radial section, as seen in Figures 3 and 11. Each of the case members has situated at a transaxial plane laterally outward from the plane of the pockets, 4, an annular channel, 5, which is provided with steam supply connections hereinafter more particularly described. From this channel, ducts 6 extend between the consecutive pockets, 4, of the innermost series 80 of casing pockets, emerging at the inner face of the casing wall on which the rotor is seated directly opposite the innermost series of rotor pockets, 1^a, for discharge of the steam into said pockets respectively, 85 said ducts being inclined with respect to the plane of rotation of the rotor circumferentially onward in the direction of rotation, as seen in Figure 10, for delivering the steam jets against the walls of the rotor pockets as indicated by the arrows, a, on 90 Figure 12, so that the jet is reflected and delivered from the rotor pocket in the direction indicated by the arrows, b, on Figure 12, into the adjacent facing pockets, 95 4, of the casing wall from which it emerged through the duct, 6. From the pockets 4, 100 105 110

ducts, 7, extend in the casing wall outwardly with respect to the rotor and inclined circumferentially onward in the direction of rotation of the rotor, as seen in Figure 6 11, into an annular channel, 8, which is formed in the casing in a manner herein-after more particularly described, and from said channel ducts, 9, approximately registering at their inner ends with the outer 10 ends of the ducts, 7, respectively, lead to the face of the casing wall for discharge into the next outer series of rotor pockets, 1^a, the direction of said ducts, 9, being inclined with respect to the plane of rotation and with respect to radial planes through their entrance ends respectively, circumferentially onward in the direction of rotation, for delivering the steam jet derived from the preceding casing pocket 15 20 into the succeeding rotor pocket with forward drive against the walls of the rotor pocket, as in the case of the entering jets through the ducts, 6, with respect to the innermost series of rotor pockets, as above described. 25 It will be understood that the steam entering for its first attack upon the rotor at the innermost series of rotor pockets is expanded and diminished in velocity at its delivery through the ducts, 9, into each successive radially outer series of rotor pockets, the entire device being dimensioned with a view to causing the expansion and diminution of velocity and pressure to correspond approximately to the increase in 30 35 circumferential speed of the rotor at the successive series of pockets due to the successively greater and greater radius of said successive series; so that the impact of the steam jets at the outermost series of pockets shall be as effective for impelling the rotor in its rotation as the initial jets directed against the innermost series of rotor pockets. The ducts, 7, leading from the casing pockets of the outermost series 40 45 lead to an annular space, 10, in the casing beyond the rotor, from which space an exhaust duct, 11, leads off tangentially, and is provided with an exhaust pipe connection as seen at 12.

50 Certain details of construction chiefly for convenience of manufacture, will now be described. Each casing member has its lateral wall with whose inner face the rotor is contiguous for its rotation, formed in two laminae having their parting plane outward from the casing wall pockets, 4. The pockets, 4, are formed on the inner face of the inner lamina, α , and through this lamina the ducts, 7, are formed registering at their outer ends with grooves, 15, treated in the foregoing description as part of said ducts, 7, said grooves extending obliquely with respect to radial planes, in the inwardly-facing surface of the outer lamina, γ , and leading 55 60 65 into the channels, 8, already described,

which are formed in the said inner face of said outer lamina, γ . The ducts, 9, are formed in the inner lamina, α , their outer ends registering with the radially outer ends of the grooves, 15, which thus connect the 70 ducts, 7 and 9, regardless of the annular channels, 8. The purpose and advantage of these annular channels is to distribute the steam, which may be delivered unequally from the several pockets, so as to equalize 75 the access of steam to all the rotor pockets of each series; and this is particularly necessary in view of the fact that for economy of construction the pockets of all the series are of the same angular extents from which 80 it results that the number of pockets in the several series increases from the center outward, the dimensions being chosen so that the differential between the circumferences of consecutive series of pockets is equal to or 85 a multiple of the circumferential distance allotted to a pocket; and but for the channels mentioned, serving to distribute the steam derived from all the pockets of one series to all the pockets of the next series, the additional pockets in the outer series might receive no steam. 90

For making steam connections to the annular channels, 5, the casing members, 2 and 3, are shown provided with radial bosses, 2^a and 3^a, which are continuous with trans-axial peripheral bosses, 2^b, and 3^b, and in these bosses steam ducts are bored leading to the annular bosses, 5^a, in which the channels, 5, are formed, the bores, 2^a and 3^a, in the 100 bosses, 2^a and 3^a, being closed at the outer ends by screwed-in plugs, 2^c and 3^c and the bore, 2^d in the transaxial boss, 2^b, is closed by a plug, 2^e; and at the entrance of the bore, 3^f, in the transaxial boss, 3^d, there is applied a fitting, 10, for receiving a screwed-in steam pipe connection. 105

It will be understood that the two casing members, 2 and 3, are machine fitted steam-tight to each other and are suitably clamped together by bolts engaging their flanges, as seen in Figures 1 and 2; and that their inner faces are machine fitted to the rotor faces with such accuracy that the water of condensation affords adequate packing. But it 110 will also be understood that other liquid packing and lubrication may be provided. 115

I claim:

1. In a steam turbine in combination with a rotor disk having a plurality of concentric series of laterally opening pockets concavely curvilinear in circum-axial section of the disk; a casing in which the rotor is fitted to revolve with its said pocketed face contiguous to a fixed wall of the casing; said wall having a corresponding plurality of concentric series of pockets opening toward the rotor disk pocket series respectively; annular channels situated laterally outward from the pockets of each series of the cas- 120 125 130

ing, and ducts from said channels extending between the pockets of the adjacent series opening at the inner face of the casing for discharge into the rotor pockets of 5 the next outward series; the innermost of said annular channels having steam pipe connections, and ducts from each casing pocket leading into the casing channels lateral to the next outer series of casing 10 pockets, for supplying to said channels steam for discharge as described into the opposed series of rotor pockets.

2. In the construction defined in claim 1 foregoing, the rotor pockets being concavely 15 curvilinear in radial section of the disk as well as in circumferential section thereof.

3. In the construction defined in claim 1 foregoing, the rotor disk having pockets as described on both sides, and the casing having 20 duplicate construction at both sides of the rotor disk.

4. In the construction defined in claim 1 foregoing, the ducts for discharge into the rotor pockets being at their discharge portion 25 inclined with respect to radial planes onward in the circumferential direction of rotation of the rotor.

5. In the construction defined in claim 1 foregoing, the ducts for discharge into the 30 rotor pockets being at their discharge portion inclined with respect to the plane of rotation of the rotor and with respect to radial planes through their discharge ends 35 respectively, for directing the steam delivered through them onward in the circumferential direction of rotation of the rotor.

6. In the construction defined in claim 1 40 foregoing, the ducts leading from the casing pocket to the annular channels being inclined forwardly in the direction of rotation from radial planes through their inlet ends respectively.

7. In the construction defined in claim 1

foregoing, the ducts from the casing pockets 45 to the annular channels opening in said channels in substantial registration with the openings from said channels of the ducts which discharge from the rotor pockets as described, both of said ducts being inclined 50 with respect to radial planes through their entrance ends forwardly in circumferential direction of rotation.

8. In the construction defined in claim 1 foregoing, the casing wall being made in 55 two laminae parting at a plane outward from the bottom or back of the casing wall pockets and cutting the ducts which connect the pockets of consecutive series.

9. In a steam turbine in combination 60 with a rotor disk having a plurality of concentric and a series of lateral opening pockets concavely curvilinear in circum- axial section of the disk; a casing in which the rotor disk is fitted to revolve with its 65 pocketed face contiguous to a relatively fixed wall of the casing, said wall having a corresponding series of pockets opening for discharge thereinto from the correspond- ing rotor pockets respectively; a series of 70 ducts through the casing wall extending between the pockets of the innermost series thereof, for discharge into the innermost series of rotor pockets; ducts from the cas- 75 ing pockets of each series being in curvi- linear paths between the consecutive pockets of the next outer series and,—except the outermost series of ducts,—discharging into the rotor pockets facing said next outer series; steam inlet connections to the first 80 mentioned series of ducts, and steam exhaust connections from the outermost series of ducts.

In testimony whereof, I have hereunto set my hand, at Chicago, Illinois, this 5th day 85 of May, 1928.

ERIC BLUCKER.
